UNITED STATES PATENT OFFICE.

HARRY H. KEEPORTS, OF CANTON, OHIO; THE GEO. O. HARTER BANK, OF CANTON, OHIO, ADMINISTRATOR OF SAID HARRY H. KEEPORTS, (DECEASED), ASSIGNOR, BY MESNE ASSIGNMENTS, TO B. WICKLIFFE TWYMAN, OF MILWAUKEE, WISCONSIN.

COUNTERWEIGHT MEANS FOR CRANK SHAFTS AND PROCESS OF FORMING AND ATTACHING.

Application filed May 27, 1920, Serial No. 384,776. Renewed August 13, 1928.

This invention relates to improved counterweight means for crank shafts for automobile engines or the like, and to the process of forging and attaching the same.

- 5 The objects of the invention are to provide an effective counterweight which can be readily and economically applied in the process of manufacture and be securely held on the crank shaft of an automobile or the like.
- 10 Objects relating to details and economies of construction and operation will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing forming a part of 20 this specification, in which:

Fig. I is a detailed side elevation view of a portion of a crank shaft, including one of the throws with my improved counterweight in place.

25 Fig. II is a detail sectional elevation view on line 2—2 of Fig. I, showing the details of construction and method of forging and application.

Fig. III is a detail transverse sectional view 30 through the counterweight and connecting head therefor, on line 3—3 of Figs. I and II.

In the drawing similar reference characters refer to similar parts throughout the several views, and the sectional views are taken looking in the direction of the little arrows at 35 the ends of the section lines.

Considering the numbered parts of the drawing, 1 is the crank shaft having a throw.

2. A counterweight 3 is formed with projecting engaging portions 3' 3' which are conformed on their inner surfaces to the extended head 4 on the crank shaft opposite the throw. A shallow groove 5 is formed around this head to which the engaging part of the counterweight conforms, as seen in Fig. III. A

40 clearance groove 7 is also made on the counterweight opposite the center of the head 4 (Fig. I). This produces a structure which can be very readily drop forged. The groove 5 can be very readily shaped with the clearance 6, and a counterweight 3 can be very readily drop forged in the shape in which it appears,

with one portion around 3' bent outwardly, as indicated by the dotted lines in Fig. II.

When the crank shaft has been forged with 55 the projecting head 4 thereon, the counterweight 3 is brought into position and the part indicated by the dotted lines is forced into position by any suitable means, thereby securing a very tight and effective joint. The 60 parts might be closed cold but it is better that same should be shrunk on. The metal where trimmed has plenty of clearance and opportunity to seat itself, owing to the clearance spaces 6 and 7.

65 Of course, the counterweight 3 and the groove 5 and the shaped projections of head 4 can be located anywhere on the crank shaft webs or arms and made any shape, as long as the surfaces interlock when in place to prevent 70 the counterweight from loosening or coming off in use. It is also possible to forge both counterweight portions 3' open and close onto the projections of head 4.

I have shown my invention in the specific 75 form preferred by me, and I desire to claim the same specifically. I desire also to claim the invention broadly, as pointed out in the appended claims.

Having thus described my invention, what 80 I claim as new and desire to secure by Letters Patent is:

1. A counterweighted crank shaft consisting of the combination of a grooved projecting head portion at the inner end of the crank 85 throw, with engaging portions thereon and a grooved surface around its periphery, and a counterweight conformed to the grooved surface to surround the periphery and closed and shrunk to position thereon.

2. A counterweighted crank shaft consisting of the combination of a grooved portion at the inner end of the crank throw, with engaging portions thereon and a grooved surface, and a counterweight conformed to the 95 grooved surface and closed and shrunk to position thereon.

3. The process of forming a counterweight for a crank shaft consisting of forming interlocking shapes on the said shaft and 100 weight, the shape on the weight being in open position, and thereafter closing and shrinking the weight in place.

4. The herein described method of securing

counter-weights to shafts, consisting in providing the shaft with an anchoring head having opposite locking shoulders on its side adjacent the shaft, providing the counter-weight 5 with a recess having cooperating locking shoulders to engage the shoulders on the anchoring head, forming the engaging surfaces of the head and counter-weight of such shape as to prevent lateral displacement of the

counter-weight, heating the counter-weight, 10 and applying the counter-weight to the anchoring head and squeezing it into interlocking engagement therewith and permitting it to shrink thereon.

In witness whereof, I have hereunto set my 15 hand,

HARRY H. KEEPORTS.
